DOOR HANDLE

Alexander Rauchman, New York, N. Y.

Application October 11, 1956, Serial No. 43,321

Term of patent 7 years

(Cl. D10—8)

Fig. 1 is a front elevational view of a door handle, showing my new design.

Fig. 2 is a side elevational view thereof.

The rear of the handle is a plain and conventional configuration.

I claim:

The ornamental design for a door handle as shown and described.

No references cited.
